DOOR LATCH

John J. McCabe, Cleveland, Ohio, assignor to The
Apex Electrical Manufacturing Company,
Cleveland, Ohio, a corporation of Ohio

Application January 3, 1935, Serial No. 257

7 Claims. (Cl. 292—220)

This invention relates to door latches and it has for its object the provision of a door latch which may be operated with a minimum of effort on the part of the operator by movement of a door handle or latch operating member in the door-opening direction. A further object of the invention relates to the provision of a self-opening hinged door having a latch and independently useable associated foot and hand operating means therefor, whereby upon operation of the latch by such means, the door swings to an open position.

With these and other objects in view, the invention consists in the novel construction, arrangement and combination of parts, hereinafter illustrated and described in some of its embodiments in the accompanying drawing, and particularly pointed out in the appended claims.

In the drawing, Figure 1 is a detail sectional view of a door latch and its operating handle illustrating one form of the invention; Figure 2 is a sectional view taken on line 2—2, Figure 1 showing the details of the foot-actuated means provided for the operation of the latch bolt; Figure 3 is a view similar to Figure 1 illustrating a similar door latch having axially shiftable handles or operating members located one on each side of the door; Figure 4 is an enlarged side elevational view, partly in section, of the handle of the door latch shown in Figure 1; Figure 5 is a view similar to Figure 4 with the parts rotated ninety degrees from the position shown in Figure 4; Figure 6 is a view corresponding to Figures 4 and 5 illustrating the details of the fixed cam member carried by the door for cooperation with a complementary member carried by the handle of the door latch; Figure 7 is a detail sectional view taken on line 8—8, Figure 6; and Figure 8 is a side elevational view illustrating the details of the means provided for automatically opening the door upon the release of its latch.

The door latch used for purposes of illustrating this invention comprises a latching device carried by a door 1 and a catch or keeper 2 carried by the door-frame 3. The latch includes a latch-bolt 4 pivoted at 5 in a latch mechanism casing or frame 6 for movement into and out of engagement with the catch 2. The operating means for the latch-bolt 4 comprises a toggle link 7 having one end pivotally secured to the latch 4 by means of a pin 8. The other end of the toggle link 7 is slotted at 10 for receiving a pin 11 carried by one end of a U-shaped toggle link 12 which is pivoted at 13 to the frame 6. The toggle links 7 and 12 normally are in substantial alignment with each other.

The ends of the pin 11 are received in the slots of hooks formed in the ends of a U-shaped member or frame 14, secured to one end of a rod 15, the other end of which is provided with an operating handle 37 by means of which movement of the rod and operation of the latch-bolt is effected. Springs 17 and 18 are provided for maintaining the door latch and its operating means respectively, in latching position. A sleeve 41 carried by the door 1 provides a guideway for the handle 17. The inner end of this sleeve is threaded at 42 for receiving the threaded boss 22 of the latch mechanism frame 6 whereby the frame is supported by such sleeve.

From the foregoing it will be seen that the opening movement of the door may be readily effected by merely pulling on the handle 37. A door opening means of this sort has considerable utility when used on refrigerators, as it often happens that the hands of the operator are burdened with articles to be placed in the refrigerator and it is sometimes much easier under such conditions to open the door by merely pulling on a knob or handle, such as shown at 37, than it is to turn a door opening crank or handle in effecting the opening of the door, particularly when the door is self-opening and when the unlatching thereof may be effected by the use of a very slight force as is the case here. The handle 37, however, is arranged to operate the latch-bolt 30 upon its being turned, as will be described in detail presently, so that a person may open the door in one or the other manner, whichever is easier.

In addition to the manual door opening means illustrated in detail in Figure 1, foot-actuated means are additionally provided for unlatching the door. The foot-operated means referred to comprises a pin 23 mounted for movement in the door-frame 3 to shift the latch-bolt 4 out of engagement with the catch or keeper 2. The pin 23 is connected to one arm of a bell-crank 24 pivoted at 25 to the door-frame. The other arm of the bell-crank 24 is connected by means of a rod 26 to one end of a fulcrum lever 27, pivoted at 30 to the bottom of the door-frame and having a foot pedal 28 at its other end.

By means of the structure just described, the door may be unlatched by either depressing the pedal 28 or by pulling upon the handle 37, whichever happens to be the more convenient for the operator. Upon release of the latch-bolt 4 from its catch 2, the door is moved to its open position by means of one or more plungers or pins 31 engaging the edge of the door to one side of the

hinge axis thereof and carried by the door-frame 2 at the side thereof adjacent to the door hinges

32. The plunger 31 is urged against the door by any suitable means such as the spring 33, all of which are illustrated in detail in Figure 8 of the drawing.

Where it is desired to have a means for unlatching the door on each side thereof, the mechanism shown in Figures 1 and 2 may be used by 10 providing the U-shaped member 14 with a cross-piece 34 to which is attached a pin 35 fixed for movement with an inner door handle or knob 36. The movement of the knob 36 in a direction towards the door will serve to release the latch-bolt 4, the same as does movement of the knob 16 in a direction away from the door. In either case, the movement of the knobs 16 or 36 is in a door-opening direction and upon release of the latch the spring 33 operates to complete or assist 15 in the opening movement of the door.

In Figures 4 to 7, there is illustrated in detail the latch-bolt operating mechanism which is provided for unlatching the door by either pulling or turning a handle 37. The handle 37 is 20 rotatably connected to a latch operating pin 38 which corresponds to the pin 18 shown in the previously described views of the drawing and differing therefrom in that the handle 37 may be turned with respect to such pin. The handle and 25 pin are rotatably held together by means of the head of a bolt 40 secured to the end of the rod 38. A sleeve 41 provided for carrying the handle 37 and mounted in the door is threaded at 42 for receiving the threaded boss 22 of the latch frame 35 6. The sleeve 41 is provided internally with a cam face 43 which cooperates with a cam face 44 of complementary form, provided on the part of the handle 37 which is rotatably received within the sleeve 41. The handle 37 includes a pin 45 40 of suitable material such as one of the aldehyde condensation products and this pin is removably held in place on the handle by means of the cap 46 which is secured to the handle by any suitable means such as the concealed screws 47. 45 Upon removal of the cap and pin just described, access may be had to the screw or bolt 40 for its securing or removal.

Unlatching of the door may be effected by the door latch mechanism shown in Figures 5 to 8, 50 by either rotating the handle 37 or by pulling the same in a door-opening direction, thus providing two different ways which may be used optionally in opening the door by means of this form of mechanism.

55. From the foregoing disclosure, it will be seen that this invention contemplates the provision of a door unlatching device which may be operated by either pulling, pushing or turning a handle, or by depressing a foot pedal, and when 60 the opening of the door is effected by pulling or pushing the handle, the movement of the handle is in the door-opening direction.

Furthermore, it is to be understood that the 65 particular forms of door latch apparatus shown and described, and the particular procedure set forth are presented for purposes of explanation and that various modifications of said apparatus and procedure can be made without departure from this invention as described in the appended claims.

Having thus described my invention what I claim is:

1. In combination, a member, a latch bolt pivoted on said member, toggle mechanism for operating the latch bolt about its pivot, a handle, 5 having rigid component parts, mounted for both rotative and reciprocative movement and means cooperatively associated with the handle and the toggle mechanism whereby either rotation or reciprocation of the handle in predetermined directions withdraws the said latch bolt.

2. A combination of elements as recited in claim 1 in which said means includes a stationary cam and rigid means on the handle riding thereagainst.

3. In combination, a latch bolt, a handle member, consisting of component parts in rigid relationship, means for mounting the handle member for reciprocative and also rotative movement, a second means connected between the handle 20 member and the latch bolt whereby reciprocative movement of the handle member in one direction causes operative movement of the latch bolt and a third means cooperatively associated with the handle member whereby rotation thereof in one 25 direction causes a predetermined degree of longitudinal or reciprocative movement.

4. A latch construction comprising, a relatively stationary member having parallel sides, a latch bolt pivoted between said sides, a toggle having 30 one end pivoted to the latch bolt and its other end pivoted to the said member, a U-shaped frame having its sides located adjacent to said toggle and interiorly of said stationary member, means for guiding the U-shaped frame for movement in 35 said stationary member, and means cooperatively connected to the U-shaped frame and the toggle whereby movement of the U-shaped frame causes retraction of the latch bolt.

5. A combination of elements as recited in 40 claim 4 and also including a handle, means for mounting the handle whereby it may be oscillated or reciprocated, means for rotatably connecting the handle to the connecting portion of the U-shaped frame, and means operatively associated 45 with the handle whereby rotation thereof causes reciprocation thereof.

6. A combination of elements as stated in claim 4 in which a handle member is connected to the U-shaped frame, said handle being rotatable, a 50 stationary axial cam located adjacent to the handle, and rigid means on the handle riding against the said axial cam for the purpose described.

7. In combination, a member, a latch bolt pivoted on said member, mechanism for operating said latch bolt about its pivot, a second member connected to said mechanism and operated thereby upon reciprocation of the second member, means for movably mounting the second member 60 in the first member whereby the second member may reciprocate, a handle member pivotally connected to the second member so as to be capable of rotating about an axis which is parallel to the path of movement of the second member, a projection on the handle member, and an axial cam adjacent to and contacted by the said projection whereby rotation of the handle member causes reciprocation of the handle member and said second member to a predetermined degree.

JOHN J. McCABE. 70
